UNITED STATES PATENT OFFICE.

FREDERICK H. EMERY, OF SCRANTON, PENNSYLVANIA.

COAL-PICKING APPARATUS.

1,119,586.

Specification of Letters Patent.

Patented Dec. 1, 1914.

Application filed April 7, 1914. Serial No. 830,152.

To all whom it may concern:

Be it known that I, FREDERICK H. EMERY, a citizen of the United States, residing at Scranton, in the county of Lackawanna and State of Pennsylvania, have invented certain new and useful Improvements in Coal-Picking Apparatus, of which the following is a specification.

My invention relates to improvements in coal picking apparatus, wherein means are provided for separating the coal from slate, bone or other foreign material.

An important object of the invention is to improve the construction of such apparatus in general, with a view of increasing their efficiency in operation.

A further object of the invention is to provide means whereby the coal is subjected to the maximum number of separations, without corresponding increase in the separating parts of the machine.

Further objects and advantages of the invention will be apparent during the course of the following description.

25 In the accompanying drawings forming a part of this specification, in which like numerals are employed to designate like parts throughout the same,

Figure 1 is a side elevation of apparatus embodying my invention. Fig. 2 is a central longitudinal sectional view through the upper half of the apparatus. Fig. 3 is a similar view through the lower half of the apparatus; Fig. 4 is a fragmentary perspective view of a chute embodied in the invention. Fig. 5 is a detailed transverse sectional view taken on line 5-5 of Fig. 1; Fig. 6 is a side elevation of the means shown in Fig. 5; Fig. 7 is a perspective view of a division plate; Fig. 8 is a similar view of a slightly different form of division plate; Fig. 9 is a similar view of a deflector.

In the drawings wherein for the purpose of illustration is shown the preferred embodiment of my invention the numerals 1 and 2 designate upper and lower sets of inclined main troughs or chutes, the main troughs or chutes in each set being arranged in stepped relation to discharge material from one to the other, as shown. These sets of main troughs or chutes may be supported in any desired manner.

The upper set of main troughs or chutes includes main troughs or chutes 3, 4, 5 and 6, and the lower set includes main troughs or chutes 7, 8, 9 and 10, which are identical

in some respects. Each main trough or chute comprises, as more clearly shown in Fig. 2 longitudinal sides 11, which are connected by suitable means such as the transverse beam 12 or the like. Each main trough or chute is vertically inclined at a desired angle, with its intake end arranged uppermost, as shown. Each main trough or chute is provided adjacent its intake end with a receiving floor or bottom 13, the same being arranged at slightly different angular positions in the different main troughs or chutes as may be required in each case. Arranged within each main trough or casing is a second floor or bottom 14, vertically inclined with respect to the main trough or casing with its intake end arranged uppermost. The floor or bottom 14 is arranged in end to end relation with the floor or bottom 13, and is spaced therefrom for a substantial distance providing therebetween an opening for a purpose to be hereinafter described.

Arranged adjacent the discharge end of the floor or bottom 14 is a separating plate 80 or slab 15, preferably formed of slate, stone or other analogous material. In the main trough or chute 3, the separating slab 15 is preferably rigidly mounted, while in the other main troughs or chutes the slab 15 is vertically adjustable, the same having the upper end thereof pivoted, as shown at 16. Each of the pivoted slabs 15 is vertically inclined, (the slab 15 in the main trough or chute 3 being also vertically inclined.) I provide means for vertically adjusting the lower or swinging end of each of the pivoted separating slabs 15 and to hold the same in adjustment at a desired angular position, such means preferably comprising a roller or cam 17, rigidly mounted upon a transversely extending rock shaft 18 which is eccentrically connected therewith. As more clearly shown in Fig. 1, the outer end of each of the rock shafts 18 has a toothed segment 19 rigidly connected therewith, and disposed exteriorly of the main trough or chute. This toothed segment is adapted to be detachably engaged by a pivoted holding dog 20, and locked thereby in adjustment at a desired angular position.

Arranged within each main trough or chute is a transversely extending rocker-feeder 21, disposed within the opening occurring between the spaced floors or bottoms 13 and 14. Each rocker-feeder is pro-

vided upon its upper side with a pocket or recess 22, adapted when the same is turned in one direction to receive the material from the receiving floor or bottom 13, and when 5 turned in an opposite direction to discharge or deliver the same upon the floor or bottom 14. The function of this rocker-feeder is to provide means for preventing the continuous passage of material from the floor 10 or bottom 13 to the floor or bottom 14, and to feed proper amounts of such material from one to the other at desired intervals.

Means are provided for simultaneously turning all of the rocker-feeders in the two 15 sets of main troughs or chutes, which will now be described.

Connected with the rocker-feeder 21 in the main trough or chute 3, to turn therewith, is an exteriorly arranged bell crank 20 lever 23, having its upper arm pivotally connected with a pitman 24, connected with an eccentric head 25. This eccentric head engages and is moved by an eccentric 26, rigidly mounted upon a drive shaft 27. 25 This drive shaft may be rotated by any suitable means. It is thus seen that the rotation of the drive shaft 27 will impart an oscillatory movement to the feeder 21 in the main trough or chute 3, and the bell 30 crank lever or levers rigidly connected therewith. Pivotally connected with the lower arm of the bell crank lever 23 is a longitudinally extending pitman 28, the opposite end of which is pivotally connected 35 with the upper end of a vertically swinging lever 29, which is rigidly connected with the rocker-feeder 21 in the main trough or chute 4. Pivotally connected with the lower end of the vertically swinging lever 29 is 40 a longitudinally extending pitman 30, having its opposite end pivotally connected with the upper end of the vertically swinging lever 31, which is rigidly connected with the rocker-feeder 21 in the main trough 45 or chute 5. The lower end of the vertical swinging lever 21 is pivotally connected with a longitudinally extending pitman 32, having its opposite end pivotally connected with the upper end of a crank or lever 33, 50 which is rigidly connected with the rocker-feeder 21 in the main trough or chute 6. Rigidly connected with the opposite end of the rocker-feeder 21 in the main trough or chute 3 is a laterally extending crank 34 55 (see more particularly Fig. 2), having pivotal connection with a depending pitman 35, having its lower end pivotally connected with the upper arm of a bell crank lever 36. This bell crank lever is rigidly connected with one end of the rocker-feeder 21 in the main trough or chute 7. Pivotally connected with the lower arm of the bell crank lever 36 is a longitudinally extending pitman 37 having its opposite end pivotally connected with the upper end of a 60

vertically swinging lever 38, which is rigidly connected with the rocker feeder 21 in the main trough or chute 8. Pivotally connected with the lower end of the lever 38 is a pitman 39, the opposite end of which 70 is pivotally connected with a vertically swinging lever 40. This vertically swinging lever 40 is rigidly connected with the rocker feeder 21 in the main trough or chute 9, and has its lower end pivotally connected with a pitman 41. The opposite end of this pitman is pivotally connected with a crank or lever 42, which is rigidly connected with the rocker feeder 21 in the main trough or chute 10. The operating means for the 75 rocker-feeders 21 in the set of main troughs or chutes 2 are arranged upon the opposite side of the same with respect to the operating means of the rocker feeders in the other set of main troughs or chutes. From the 80 foregoing description it is obvious that all of the rocker-feeders are simultaneously turned or oscillated.

Arranged within the lower or discharge end of each of the main troughs or chutes is 90 a longitudinally adjustable regulating plate 43, (see Figs. 2, 7 and 8) such regulating plates being provided with extensions mounted to reciprocate within longitudinal slots 44, formed through the sides 11 as 95 shown. Secured to the lower surfaces of each regulating plate are rack bars 45, there being preferably one rack bar adjacent each end of the regulating plate. These rack bars are engaged and moved by pinions 46, 100 rigidly mounted upon transverse rotatable shafts 47. Each of these transverse rotatable shafts, as more clearly shown in Fig. 6, has its outer end formed polygonal in cross section, to be engaged with and turned by a 105 wrench or the like, not shown. Rigidly mounted upon the outer end of the rotatable shaft 47 is a toothed wheel 48, detachably engaged by a holding pawl 49. It is thus seen that means are provided to reciprocate 110 or move each regulating plate in either direction with respect to its main trough or chute, and to lock the same in adjustment at a desired longitudinal position with relation thereto. Pivotally connected with the upper 115 intake edge of each regulating plate is a division plate 50, as more clearly shown in Figs. 7 and 8. As shown in Fig. 8 each division plate 50 may preferably have its intake or discharge edge provided with a protecting element or casing 51' which may be formed of hard rubber or other analogous material. The division plate is adapted to be angularly adjusted with relation to the regulating plate and for this reason it is 120 provided with an upstanding crank 51 rigidly connected therewith. The upstanding cranks 51 in the main troughs or chutes of the set 1 are all pivotally connected with 125 and moved by a longitudinally extending 130

rod or pitman 52, which is pivotally connected, as shown at 53 in Fig. 1, with a vertically extending manually operated lever or crank 54. This lever or crank is pivoted at its lower ends, as shown at 55, and is provided with clamping means 56, whereby the same may be locked in adjustment at a desired angular position. The means to simultaneously swing all of the upstanding cranks 51 in the 10 main troughs or chutes of the lower set 2 is identical with the corresponding means hereinbefore described wherefore it is thought that no further description of the same is necessary. As more clearly shown in Figs. 15 2 and 3, each division plate 50 is spaced a substantial distance from the discharge edge of the separating slab 15, providing an opening or space 57 therebetween, at which point the separation of the coal, slate, or bone 20 takes place, in a manner to be more fully described.

As clearly shown in Fig. 2, a deflector element or receptacle 58 (which is curved in cross section and more clearly shown in Fig. 9) is arranged within or below the space or opening 57 between the separating slab 15 and the division plate 50. This deflector element is preferably angularly adjustable, for which reason the ends 59 thereof, see Fig. 9, 30 are rigidly mounted upon a rock shaft 60 journaled through the longitudinal sides 11. An upstanding crank 61 (see Figs. 9 and 1) is rigidly connected with one end of the rock shaft 60 and is angularly adjusted by 35 means of a pivoted cam 62 as shown. The material deflected by the deflector element 58 passes from the lower end thereof into a rearwardly extending depending chute 63, discharging onto the intake end of the receiving floor or bottom 13 of the main trough or chute 7, as clearly shown in Fig. 2.

Pivotally connected with the discharge or lower end of each of the main troughs or chutes except troughs or chutes 6 and 10, as 45 shown at 64, is a vertically adjustable conducting chute 65, the discharge end of each conducting chute passing into the intake end of each successive conducting chute, as shown. As above stated, each conducting 50 chute 65 is vertically adjustable, or may be swung up and down to increase or decrease the distance between the separating slab 15 and the same, depending upon the character of coal being treated. The conducting chute 55 65 has its longitudinal sides provided near the pivots 64 with transversely curved slots 66 receiving clamping bolts 67 (see Fig. 1) whereby the conducting chute may be locked in adjustment at a desired angular position. 60 Pivots connected, as shown at 68, with the discharge end of the lowermost conducting chutes 65, is a checking or retarding element 69, having its bottom 70 preferably curved in cross section as clearly illustrated 65 in Fig. 3. These retarding or checking ele-

ments are angularly adjustable and are provided with curved slots 71 to receive a clamping bolt 72 whereby they may be locked at a desired angular position. The function of these checking elements is to prevent the finally treated or separated coal from being thrown to great distances from the outlet ends of the lowermost conducting chutes 65.

The conducting chute 65' in the main 75 trough or chute 9 is slightly altered in construction, the same being foreshortened and provided at its lower outlet end with spaced discharge chutes 73, there being an upstanding substantially V-shaped deflector 74 arranged within the chute to cause the coal to pass to the chutes 73. These chutes discharge into the lowermost conducting chute 65 in the lower set 2 of main troughs or chutes. The function of this construction is 80 to provide a space 75, for the passage of a forwardly extending depending return chute 76, the lower end of which discharges material onto the receiving floor or bottom 13 of the main trough or chute 10, in advance 85 of the rocker feeder 21 thereof, as clearly illustrated in Fig. 3. The upper end of the return chute 76 is arranged below and connected with the lower end of the main trough or chute 6, below the discharge end 90 of the separating slab 15 thereof. There is an inclined deflector 77 arranged within the upper end of the return chute 76.

The operation of the apparatus is as follows:—The coal with the slate, bone or other foreign material mixed therewith is primarily fed onto the receiving floor or bottom 13 of the main trough or chute 3. This material, upon the turning movement of the rocker-feeder 21 toward the floor base 100 13 passes into the pocket 22 to fill the same, and when the rocker feeder 21 is rotated in a reverse direction, is discharged upon the floor or bottom 14. The coal and slate mixed therewith travels downwardly by 105 gravitation upon the separating slab 15, and the first separating action occurs at the discharge end of this slab. The heavier particles of slate with some coal mixed therewith drop into the deflector 58 and pass 110 through chutes 63, to be passed through the main troughs or chutes in the lower set 2. The separating operation within these troughs or chutes will be described later. The other portion of the coal with the 115 lighter particles of slate jump across the opening 57 in the main trough or chute 3 at which time a second separating action occurs. The heavier particles of coal and slate drop downwardly upon the receiving floor or bottom 13 in the main trough or chute 4, while the coal free from the slate passes onto the division plate 50 in the lower end of the main trough or chute 3, and subsequently passes through the conducting 120 125 130

4

chutes 65 to be finally discharged from the outlet end of the lowermost conducting chute 65. The operation is repeated in each successive main trough or chute, the coal free from slate being fed into the conducting chute 65 of each main trough or chute. In the main trough or chute 6 the heavy bone and slate is discharged into the return chute 76, and fed thereby onto the receiving floor or bottom 13 in the main trough or chute 10, to be finally subjected to a separation when the same passes the discharge edge of the separating slab 15 thereof, the slate passing down as indicated by the arrows, while the coal free from the slate is discharged from the lower edge of the regulating grate 43 thereof, as indicated by the arrows. In the lower set 2 of the main troughs or chutes, a similar separating action takes place in each main trough or chute, the coal free from the slate or the like being successively fed into the conducting chutes 65. The coal and slate finally pass onto the floor or bottom 13 in the main trough or chute 10, and together with the coal and slate fed through the return chute 76, are subjected to the final separating action, as hereinabove explained. It is thus seen that by the peculiar arrangement and coöperation of the main troughs or chutes, which are eight in number, I am able to obtain ten separating actions.

It is to be understood that the form of my invention herein shown and described is to be taken as the preferred examples of the same, and that various changes in the shape, size and arrangement of parts may be resorted to without departing from the spirit of the invention or the scope of the subjoined claims.

Having described my invention what I claim is:—

1. In apparatus of the character described, a plurality of main inclined chutes arranged in stepped relation to discharge material from one to the other, separating means arranged within each main chute between the ends thereof, and a conducting chute pivotally connected with the outlet end of the upper main chute, extending longitudinally of and beyond a lower main chute and movable vertically toward and away from the separating means of the lower main chute in accordance with the size of the material being treated.

2. In apparatus of the character described, a plurality of inclined main chutes arranged in end to end relation, a pivoted separating plate arranged within each main chute, means to raise and lower the free end of each separating plate, a regulating plate mounted in each main chute below the separating plate, means to move the regulating plate toward and away from the separating plate, a division plate pivoted to the regulat-

ing plate to be angularly adjusted with relation thereto, means to swing the division plate in a vertical plane, a plurality of conducting chutes arranged above the main chutes and receiving material from the regulating plates and discharging material from one to the other, and means to vertically swing each conducting chute toward and away from its corresponding main chute.

3. In apparatus of the character described, upper and lower sets of inclined main chutes, separating means disposed in each main chute, conducting chutes arranged above the main chutes in the lower set to receive material from the separating means thereof, one of the conducting chutes being forked at its lower end to provide an opening, and a depending return chute receiving material from the separating means in the lowermost main chute of the upper set and having its lower end passing through said opening to discharge material into the lowermost main chute in the lower set in advance of the feed means therein.

4. In apparatus of the character described, upper and lower sets of inclined main chutes, separating means arranged in the main chutes, conducting chutes arranged above the main chutes in the lower set to receive material from the separating means thereof, one of said conducting chutes being provided with an opening in its bottom, and a return chute receiving material from the separating means in one main chute of the upper set and having its end passing through said opening to discharge material into one main chute in the lower set in advance of the separating means therein.

5. In apparatus of the character described, upper and lower sets of inclined main chutes, the main chutes in each set being arranged in stepped relation, separating means arranged within each main chute; and a set of conducting chutes arranged near each set of main chutes, the conducting chutes in each set being arranged in stepped relation to discharge material from one to the other, receiving material from the outlet ends of the main chutes, and vertically adjustable to be moved toward and away from the separating means in accordance with the size of the material being treated, and depending chutes to feed material from the end main chutes in the upper set to corresponding end main chutes in the lower set, whereby a part of the material passing through certain of the main chutes in the upper set pass through certain of the main chutes in the lower set.

6. In apparatus of the character described, upper and lower sets of inclined main chutes, the main chutes in each set being arranged in stepped relation; separating means arranged within each main chute; a set of conducting chutes arranged near each

- set of main chutes, the conducting chutes in each set being arranged in stepped relation to discharge material from one to the other, receiving material from the outlet ends of the main chutes, and vertically adjustable to be moved toward and away from the separating means in accordance with the size of the material being treated; and return chutes receiving material from certain of the main chutes in the upper set in proximity to the separating means thereof and discharging the same into certain of the main chutes in the lower set near the intake ends thereof.
- 10 7. In apparatus of the character described, upper and lower sets of inclined main chutes, the main chutes in each set being arranged in stepped relation; separating means arranged within each main chute;
- 20 a set of conducting chutes arranged near each set of main chutes, the conducting chutes in each set being arranged in stepped

relation to discharge material from one to the other, receiving material from the outlet ends of the main chutes, and vertically adjustable to be moved toward and away from the separating means in accordance with the size of the material being treated; return chutes receiving material from certain of the main chutes in the upper set in proximity to the separating means thereof and discharging the same into certain of the main chutes in the lower set near the intake ends thereof; and a vertically adjustable deflector arranged in the upper intake end of one of the return chutes below and in proximity to the separating means.

In testimony whereof I affix my signature in presence of two witnesses.
